W. C. LANG.

GRAIN DOOR.

FILED MAY 2, 1921.

UNITED STATES PATENT OFFICE.

WILLIAM C. LANG, OF SUPERIOR, WISCONSIN.

GRAIN DOOR.

Application filed May 2, 1921. Serial No. 466,074.

To all whom it may concern:

Be it known that I, WILLIAM C. LANG, a citizen of the United States, residing at Superior, in the county of Douglas and State 5 of Wisconsin, have invented certain new and useful Improvements in Grain Doors, of which the following is a specification, reference being had therein to the accompanying drawing.

10 This invention relates to certain improvements in car doors and has special reference to what is commonly called a grain door for railroad cars.

15 The principal object of the invention is to provide a door having improvements over what is at present known in the art.

Other objects and advantages of the peculiar construction will appear in the further description of the invention.

20 In the accompanying drawing forming part of this application and in which like reference characters indicate like parts:

Figure 1 is a transverse sectional view through the car door opening fitted with one 25 of the improved attachments and the grain door partly in place, the covering plate of the door post being removed;

Figure 2 is an outside elevation of the car having my improved door attached 30 thereto:

Figure 3 is a vertical sectional view of the uppermost end of a door post illustrating the arrangement of sheaves over which the operating line is reeved:

35 Figure 4 is a horizontal sectional view through one of the car door posts in which the door engaging operating line reciprocates, and

Figure 5 is a plan view of the operating 40 hand wheel and its cooperative parts.

1 represents the usual door opening in the side of the car 2. Upon either side of the door opening is installed a vertically disposed, rectangularly shaped, door post 3.

45 The door post 3 has formed therein two vertical rectangular slots, or cut away portions, the entire length thereof, in either corner adjacent the door opening, as at 4-4, and which slots may be reinforced by 50 suitable channel irons 5-5 and the metal covering plate 6.

Approximately one-third of the distance down from the upper edge of the door and adjacent each side thereof is pivotally attached a suspending chain 24, there being

eye-bolts 25 fixed to the door to provide for such attachment.

Members 26, having eyes therein, are fastened to the under side of the roof of the car from which the chains 24 pivotally depend. 60 The door being thus pivotally suspended adjacent its uppermost edge will, when raised by the operating line 27, assume a horizontal elevated position adjacent the ceiling of the car as illustrated in dotted lines in Fig. 65 ure 1.

A short length of pipe 7 is installed in each door post adjacent the uppermost end thereof, the pipe being the same length as the width of the door post and pivotally supporting the small sheaves 8-8 and the larger sheave 9. Slotted openings are formed in the bottom of the pipe so that the operating line may freely pass therethrough.

75 Each operating line is securely fastened as at 10 to the bottom of the door 11, and passes through a suitable hole adjacent the bottom of the door into the innermost channel 4, up through the slotted openings and over the sheaves in the pipe 7 and down the other channel 4 through suitable openings in the floor of the car and is fastened to the operating drum 12 fixed to the shaft 13 which is rotatably supported beneath the 80 bottom of the car by the brackets 14 and 15.

The bracket 15 is channel shaped in plan view and supports one end of the shaft 13, having the beveled gear 16 secured thereto, and the short stub shaft 17, to which is securely fixed the beveled gear 18 which meshes with the gear 16. An operating wheel 19 is fixed to the outer end of the shaft 17 and by the rotation of which the door may be readily raised or lowered.

95 I have shown a wedge shaped member 20, having a shoulder 21 formed thereon, as attached to the uppermost end of the door post and which is for the purpose of moving the door horizontally, when being 100 raised to its uppermost position, away from the door post 3 sufficiently so that the upper end of the door will rest in the bracket 22 rigidly fixed in any desired manner to the roof of the car, the shoulder 21 being for 105 the purpose of limiting the upward movement of the door.

On the outer face of the wedge shaped member and above the shoulder 21 thereon is securely fixed a flat leaf spring 23, the 110

free end of which is bent outwardly and downwardly in spiral form for engagement with the face of the door as it is raised to adjacent its ultimate uppermost position 5 and by which engagement the free end of the spring is forced upwardly causing it to impart a constant downward pressure upon the door. This is for the purpose of affording assistance when it is desired to close the door 10 as when the hand-wheel 19 is slackened away for the purpose of allowing the door to drop into position the pressure exerted by the springs 23 will impart initial downward motion to the lower edge of the door and 15 thus assist in automatically closing same.

Having thus described my invention what I claim and desire to secure by Letters Patent, is:

1. A pivotally suspended door of the character described for railway cars having a horizontally disposed shaft for operating same externally of the car, lines one end of

each of which is wound about the shaft and the opposite end attached to the door, door posts, each of said lines operating in spaced 25 channels in the corners of their respective door posts.

2. The combination with a grain door for cars which is closable against the posts of the door opening and slideable vertically against 30 said posts, of slots formed in the two opposite corners of each of the posts facing the opening, sheaves mounted at the upper ends of the posts, flexible means operative within the slots over the sheaves and attached to 35 the door, and a manually operated shaft beneath the door externally of the car for operating the flexible means.

In testimony whereof I hereunto affix my signature in the presence of two witnesses. 40

WILLIAM C. LANG.

Witnesses:

MICHAEL M. TIERNEY,
S. GEO. STEVENS.
